GUSTAVE M. FAUSER, OF ARDSLEY ON HUDSON, NEW YORK, ASSIGNOR TO CONGOLEUM-NAIRN, INC., A CORPORATION OF NEW YORK

DESIGN FOR A RUG

Application filed November 10, 1930. Serial No. 37,594. Term of patent 3½ years.

To all whom it may concern:

Be it known that I, GUSTAVE M. FAUSER, a citizen of the United States of America, residing at Ardsley on Hudson, in the county of Westchester and State of New York, have invented a certain new, original, and ornamental Design for a Rug, of which the following is a specification, reference being had to the accompanying drawing forming a part hereof.

The figure is a plan view of a section of a rug showing my new design. The illustrated body section of the rug bounded by the indicating lines $a-a'$, $b-b'$, $c-c'$ and $d-d'$ forms a complete unit and such unit is repeated throughout the entire body of the rug in

the relation wherein the angle formed by the intersection of the lines $a-a'$ and $d-d'$ coincides with the angle $b-f-f'$. The illustrated border section of the rug bounded by the indicating lines $a-a'$ and c is continuously repeated throughout the border of the rug; and the illustrated border corner bounded by the indicating lines $a-a'$ and $d-d'$ is repeated in proper relation in the other three corners of the rug.

I claim:

The ornamental design for a rug substantially as shown and described.

In testimony whereof, I affix my signature.

GUSTAVE M. FAUSER.
